UNITED STATES PATENT OFFICE.

JOHN G. MIDGLEY, OF SALT LAKE CITY, UTAH.

STEAM-HEATING SYSTEM.

1,081,509.

Specification of Letters Patent. Patented Dec. 16, 1913.

Application filed February 24, 1913. Serial No. 750,220.

To all whom it may concern:

Be it known that I, JOHN G. MIDGLEY, a citizen of the United States, residing in Salt Lake City, in the county of Salt Lake and 5 State of Utah, have invented certain new and useful Improvements in Steam-Heating Systems, of which the following is a specification.

My invention relates to steam heating apparatus of the class in which two systems of pipes are employed,—one a radiator supply system, and the other a return system from the radiators to the generator. Such 10 systems, known as gravity systems, may be operated under either high or low pressure or under vapor or atmospheric pressure in the return system, or by vacuum in the return system. My improvements are, however, preferably embodied in what is known 15 as a low pressure gravity return system in which there is a differential of pressure in the two pipe systems, the radiators being supplied with steam under low pressure and the air and water of condensation from the 20 radiators being passed through suitable valves which prevent the passage of steam. In such systems while efficient means have been provided for withdrawing air and water of condensation from the radiators, diffi- 25 culties have been experienced in properly separating the air and water in the return system and in returning the water of condensation to the generator. A rise in pressure in the generator often causes water to 30 pass from the generator into the return pipes destroying the low pressure therein and preventing the radiators from being properly emptied of air and water so that 35 they do not receive sufficient steam to heat them. It is highly desirable that there 40 should be a constant differential of pressure in the supply and return systems in order that the air and water of condensation may be most effectively withdrawn from the 45 radiators and I purposely provide for such a condition, but I also provide means whereby such differential of pressure may be maintained under all normal conditions, the 50 low pressure in the return system being always such that the air and water from the radiators may be properly withdrawn and separated, and the water of condensation being delivered to the generator no matter 55 what may be the pressure therein or to what extent the water may oscillate.

In carrying out my invention I provide the generator and radiators with a system of supply and return pipes and equip each radiator with a valve for passing air and water of condensation to the return system and preventing the passage of steam thereto, and in the return system I provide a separator from which air passes to the atmosphere, while the water of condensation in the return system passes back to the generator. The supply main is provided with one or more pipes which receive drip or water of condensation therein and return it to the generator, and means is provided of the kind shown in Letters Patent of the United States No. 963,613 granted to me on July 5, 1910, for promoting the flow of water under different pressures and temperatures from different parts of the system to the generator. 60 65 70 75

In my patent just mentioned, means is shown for causing the water under various pressures and temperatures from different parts of the system to so flow toward the generator that any tendency of such returning water to pass back in the return system is prevented. Such apparatus operated satisfactorily under some conditions, i. e., when the pressure in the generator is relatively low, or when the differential of pressure in the two systems is not large, but when the pressure is considerable in the generator or in the supply system, or a great differential of pressure in the two systems exists the apparatus shown in my patent will not produce the desired results. I have now however provided means whereby the rise of water in the return system to an injurious extent is prevented under all pressures and condition. I do this by interposing between the separator and the generator and above the water line in the generator means which are normally open to allow the passage of water to the generator when the pressure therein is low or normal but which closes when the pressure unduly rises when the differential in pressure in the two systems is great, or when oscillations in the generator are such as to tend to cause water to pass from the generator to the return system. I have also provided the system with what I call a static head which is connected with the separator and has in its upper portion a valve which permits air to pass from the system but prevents it from entering it 80 85 90 95 100 105 110

and when the pressure in the generator or in the return system is such that communication is cut off between the separator and the generator and water of condensation rises in the return system to such an extent as to form a static head, then said static head so operates as to open communication between the separator and the generator and permit water to flow freely from the return system to the generator.

In the accompanying drawings I have shown my improvements embodied in a low pressure gravity return steam heating apparatus in which separate supply and return pipes are employed and in which a differential of pressure is maintained between the two systems, air being allowed to escape but prevented from entering the system, and the air and water of condensation being separated in a tank employed for this purpose. Some features of my invention, however, may be embodied in other systems operating under relatively high pressure, under vacuum, or under vapor or air pressure.

Figure 1 is a diagram of a steam heating system embodying my improvements in the preferred way. Fig. 2 is a detail view in section illustrating a device which I may employ for closing communication between the separator and the generator.

The radiators A are connected with the generator B by means of a supply system C. Each radiator is provided at the bottom with a valve D which permits air and water of condensation to pass from the radiators, but prevents the passage of steam therethrough. Such valves are well known in this art and each of such valves communicates with a return system E which connects with a separator F of well known construction. From the separator rises a pipe G having at its upper end or in its upper portion a valve H which under normal conditions permits the passage of air from the separator to the atmosphere but prevents the entrance of air to the return system. A drip pipe I conveys water of condensation in the supply system to the generator and a pipe J conveys water from the separator to the generator. These pipes I and J extend into a return section K of the kind shown in my patent before mentioned and they cause the streams of water, which are of different temperatures and under different pressures, to flow in parallel streams for a time before mingling in such way, as described in my before mentioned patent, as to prevent the water in one part of the return system from rising in another part thereof when the differential of pressure in the two systems would otherwise cause it. The return section K is located below the water line in the generator as mentioned in my patent before referred to. Such apparatus operates under some conditions,—as when

the generator pressure is low or the differential is not great, to cause the water to pass freely from the return system to the generator, but in order to render the apparatus efficient under all conditions I interpose between the separator and the generator means located above the water line in the generator and also in the return pipe J which is normally open to allow water to pass from the return system to the generator and which permits the apparatus indicated at K to operate in the manner before described under some conditions but which will, when the pressure in the generator rises or the differential of pressure in the two systems varies, close communication between the separator and the generator and thus prevent water from passing from the generator into the return system. Preferably the device L used for this purpose is of the kind shown in Fig. 2. It comprises a casing l connected at l' with the separator and at l² with the pipe J. Within the casing is a float M normally resting on a support m and having at its upper end a valve m' which when the float rises sufficiently is seated at m². As before stated the valve m' is normally open and allows the apparatus K to operate under normal conditions. If, however, the pressure in the generator increases, or the differential in the two systems is such as to cause water to rise or tend to rise through the pipe J to the return system, or to the separator, the float M will rise and cause the valve to close communication between the pipe J and the return system. It is evident that no water is normally contained in the casing l and hence the valve m' is normally open. Said valve m' is located above the water level of the generator and is also located above the normal water level in the return pipe J. If water rises in the casing the float will rise and close the valve before any water can reach the valve seat and the more the water rises and the greater the pressure below the float the more secure will the closure be. By this apparatus it is very clear that it is impossible for the water from the boiler to back up through the pipe J into the separator or into the return pipes above the separator because as soon as the water rises in the valve casing l to any considerable extent, the float M is buoyed up and closes communication between the pipe J and the separator at the valve seat m² and no water can thereafter rise beyond said valve seat until the static pressure above it is sufficient to open the valve. It will be understood that normally the valve is open and permits water of condensation to pass it freely, and that the normal level of water in the pipe J is at the same elevation as the water in the boiler. The valve m' operates only under abnormal conditions.

In all steam heating systems there is an up and down or oscillating motion of the water in the generator constantly going on. If the float and valve above referred to were 5 located below the water line in the generator these oscillations would be communicated to the valve and water would pass it and fill the return system, but by locating these devices above the water line of the 10 generator and below the separator such oscillations have no injurious effect and the valve remains tightly closed even when the generator pressure is very great and the 15 oscillations are very pronounced. The devices shown in Fig. 2 are simple and efficient but others may be used for the same purpose.

It will thus be seen that I have provided a steam heating system in which a differential of pressure may be obtained, this differential of pressure being produced in the 20 return system by the downward flow of water of condensation to the generator, by the passage of air out of the system and 25 by the vaporization of the water of condensation which passes from the radiators. Under normal conditions water does not rise in the static head pipe G, but when the pressure in the generator is such as to 30 close the valve at L, or the differential in pressure is such as to do this, the water of condensation passing into the separator F rises and fills the pipe G and is forced up into it by the pressure of steam or vapor, 35 under these abnormal conditions, contained in the return system. Water will continue to rise in the pipe G as long as the boiler pressure is excessive and holds the valve at L closed, but when the water in the pipe G 40 has risen to a sufficient extent it will overcome the boiler pressure and cause the valve at L to open so that water may pass from the separator to the generator, the static head however being maintained during 45 these abnormal conditions. As soon, however, as the boiler pressure is reduced, water will fall in the pipe J and the water level in the static head pipe G will be lowered until when normal conditions are assumed 50 there will be no water in the pipe G but air may freely pass through this pipe, while the water of condensation passing from the return pipes to the separator may pass by the valve at L and through the pipe J to 55 the generator. The water rising in the static head pipe is, of course, below the boiling point and does not vaporize at the top of such column of water, hence there is no tendency for it to rise to such an extent as 60 to overflow.

It will thus be seen that I have provided a system in which a differential of pressure is maintained under normal conditions and the devices K ordinarily operate efficiently 65 to prevent water from passing from the gen-

erator to the return systems, but when the generator pressure increases beyond the power of the devices K, or the differential in pressure is too great, the other devices which I have described operate with absolute certainty to prevent at any time the rise of water from the generator into the return system, and I have also provided means whereby when water is prevented from flowing from the return system to the boiler, 70 it forms a static column which, when it reaches proper elevation, opens communication between the return system and the generator permitting water of condensation to flow back to the generator in the normal 75 way, such devices being so constructed and arranged that when the generator pressure falls, the static column also falls and the static pipe is finally emptied and then becomes a ventilating pipe for the return system. 80

I claim as my invention:—

1. A steam heating system, comprising radiators, a generator, a supply system connecting the generator with the radiators, a 90 separate return system from the radiators to the generator, valves at the bottom of the radiators which permit air and water of condensation to pass to the return system but which prevent the passage of steam thereto, a valve casing connected in the return system and located above the normal water level in the return pipe and a valve device in said casing located above the normal water line in the return system for 95 closing communication above said water line between the return system and the generator whenever water tends to pass from the generator to the return system by reason of an increased pressure in the generator, or 100 a differential of pressures in the system. 105

2. A steam heating system, comprising radiators, a generator, a supply system connecting the radiators and generator, a separate return system from the radiators to the 110 generator, valves interposed between the bottom of the radiators and the return system for permitting air and water of condensation to pass to the return system but which prevent the passage of steam thereto, a separator into which the air and water of condensation passes, means for conveying the separated air to the atmosphere, devices for preventing air from passing from the atmosphere to the return system, a connection 115 between the separator and the generator, a valve casing in said connection between the separator and the generator, and a valve device in said casing located above the normal water level in the return system for closing 120 communication above said water line between the separator and generator whenever water tends to pass from the generator to the separator. 125

3. A steam heating system, comprising ra- 130

diators, a generator, a supply system connecting the radiators with the generator, a separate return system from the radiators to the generator, valves interposed between the bottom of the radiators and the return system for permitting the passage of air and water of condensation to the return system but which prevent the passage of steam thereto, a separator in the return system to 10 which air and water of condensation are delivered, means for conveying air from the separator to the atmosphere, devices for preventing the entrance of air to the separator, a pipe connection between the separator and the generator, a valve casing in said pipe connection located below the separator and above the normal water level in the return system and a valve in said casing for closing communication above said water line between the separator and generator whenever water tends to pass from the generator to the separator.

4. A steam heating system, comprising radiators, a generator, a supply system connecting the radiators with the generator, a separate return system from the radiators to the generator, valves interposed between the bottom of the radiators and the return system for permitting air and water to pass from the radiators to the return system but which prevent the passage of steam thereto, a separator in the return system to which air and water are delivered, means for conducting air from the separator to the atmosphere, devices for preventing the entrance of air to the return system, a connection between the separator and the generator and a float valve interposed in such connection located above the normal water level in the return system and which closes when water passes from the generator toward the separator before such water reaches the point of closure.

5. A steam heating system, comprising radiators, a generator, a supply system connecting the radiators with the generator, a separate return system from the radiators to the generator, valves interposed between the bottom of the radiators and the return system for permitting air and water of condensation to pass from the radiators to the return system but which prevent the passage of steam thereto, a separator in the return system where air and water of condensation are separated, connections between the separator and the generator whereby water of condensation passes back to the generator, a valve device located above the normal water level in the return system for closing communication above said water line between the generator and the separator when the water from the generator tends to pass to the separator and a pipe connected with the separator provided with a valve 65 which permits air to pass from the sepa-

rator to the atmosphere but prevents the entrance of air thereto and which pipe is adapted to receive a head of water from the return system which when sufficient opens communication between the separator and the generator.

6. A steam heating system, comprising radiators, a generator, a supply system connecting the radiators with the generator, a separate return system from the radiators to the generator, valves interposed between the return system and the bottom of the radiators for permitting air and water of condensation to pass from the radiators to the return system but which prevent the passage of steam thereto, means for conducting air from the return system to the atmosphere and for preventing the entrance of air thereto, means whereby separate streams of water returning to the generator from different parts of the system are caused to flow substantially parallel with one another before mingling and entering the generator for overcoming and equalizing the differential of pressure existing in the system and preventing the flow of water from one part of the system back into another part thereof, and a valve device located above the normal water level in the return system for closing communication above said water level between the generator and the return system whenever the pressure in the generator rises to a considerable extent or when the differential of pressure in the supply and return systems is such as to tend to cause water to pass from the generator into the return system.

7. A steam heating system, comprising radiators, a generator, a supply system connecting the generator with the radiators, a separate return system from the radiators to the generator, valves at the bottoms of the radiators through which air and water of condensation pass from the radiators to the return pipes, and a float valve in the return system located above the normal water level in the return system for closing communication above said water level between the return system and the generator whenever water tends to pass from the generator to the return system and before water rises to said point of closure.

8. A steam heating system, comprising radiators, a generator, a supply system connecting the generator with the radiators, a separate return system from the radiators to the generator, valves at the bottom of the radiators which permit air and water of condensation to pass to the return system but which prevent the passage of steam thereto, a pipe connected with the return system through which air passes therefrom to the atmosphere and in which a static head may be formed by water of condensation from the return system, means for pre-

venting the admission of air from the atmosphere to said pipe, a valve casing connected with the return system and with the generator located above the normal water level in the return system, and a valve device in said casing for closing communication above said water line between the return system and the generator whenever water tends to pass from the generator to the return system by reason of an increased pressure in the generator, a differential of pressure in the system, or the oscillations of water in the generator, said closing means being in communication with said static head whereby when said static head reaches a certain elevation said closing means may be opened thereby.

9. A steam heating system, comprising radiators, a generator, a supply system connecting the generator with the radiators, a separate return system from the radiators to the generator, valves at the bottom of the radiators which permit air and water of condensation to pass to the return system but which prevent the passage of steam thereto, means for conveying drip water from the supply system to the generator, a valve in the return system located above the normal water level in the return system which is normally open but which closes communication above said water line between the return system and the generator whenever water tends to pass from the gen-

erator to the return system by reason of an increased pressure in the generator. 35

10. A steam heating system, comprising radiators, a generator, a supply system connecting the generator with the radiators, a separate return system from the radiators to the generator, valves at the bottom of the radiators which permit air and water of condensation to pass to the return system but which prevent the passage of steam thereto, a separator into which the air and water of condensation passes, means for conveying the separated air to the atmosphere, devices for preventing air from passing from the atmosphere to the return system, a connection between the separator and the generator, a normally open valve interposed in said connection and located above the normal water level in the return system for closing communication above said water line between the separator and generator whenever water tends to pass from the generator to the separator but which under normal conditions is open and permits water of condensation to flow from the separator to the generator. 45 50 55

In testimony whereof, I have hereunto 60 subscribed my name.
